UNITED STATES PATENT OFFICE.

ARTHUR L. CHURCH, OF PHILADELPHIA, PENNSYLVANIA.

TRUCK.

SPECIFICATION forming part of Letters Patent No. 623,463, dated April 18, 1899.

Application filed June 1, 1896. Serial No. 593,841. (No model.)

To all whom it may concern:

Be it known that I, ARTHUR L. CHURCH, a citizen of the United States, residing in Philadelphia, Pennsylvania, have invented certain

5 Improvements in Trucks, of which the following is a specification.

The object of my invention is to make a car-truck that will be perfectly rigid and comparatively light and cheap. I utilize in the 10 main parts of the truck shapes that can be procured in the open market.

My invention is especially applicable to the trucks of electric locomotives where a certain amount of room is required for the motors; 15 but it will be understood that the invention can be used in connection with any rolling-stock.

In the accompanying drawings, Figure 1 is a plan view of my improved truck-frame. Fig. 2 is a side view. Fig. 3 is a section on the line 3 3, Fig. 1. Fig. 4 is a detached perspective view of the main frames composing the truck. Fig. 5 is a detached perspective view of one of the stiffening-plates. Fig. 6 is a sectional view on the line 6 6, Fig. 1; and Figs. 7 and 8 are views of modifications.

The side frames A and transom or cross-frame B are made up of wide channel-beams having shallow flanges, as clearly shown in 30 Fig. 4.

The channel-beams D form the outside plates of the two side frames, and the channel-beams D', which are bent as shown in Fig. 4, form the transom and the inside plates of 35 the side frames.

The beams D and D' are bolted or riveted together, as shown in Fig. 1, suitable spacing plates or sleeves being inserted between the parts at proper intervals. These channel-beams can be procured in the open market, 40 and the beams D' can be bent by an ordinary hydraulic press. The ends of each plate are cut away so as to form the openings d for the boxes of the axles, and to the ends d' are attached the movable pedestals E, the pedestal E' being rigidly secured to the plates. The pedestal E has a pivot-pin e, on which it swings 45 and is held in place not only by the link E', but also by a bolt e', passing through the plates D D' and through an opening in the pedestal. A flange e' on the pedestal rests against the under side of the plates, so that

when the pedestal is in position it is perfectly rigid; but when the link is detached and the bolt drawn it can swing on its pivot, so as to 55 allow for the ready removal of the box.

In order to add strength and stiffness to the structure, I mount at the junction of the side frames and transoms, above and below the channel-beam, plates D², one on the upper side 60 and one on the under side. These plates are simply sheared from ordinary sheet metal, requiring no special tools, and are riveted or bolted to the flanges of the channel-beams. The top plates D² have at one side openings 65 d² for the reception of one of the levers of the braking mechanism, as shown in Fig. 7.

Plates D³ extend from one transom to the other on each side of the center plate e at the top to stiffen the structure. The under side 70 is preferably left clear for the ready removal of the springs when necessary.

The bolster F is made of a flanged channel-beam and is preferably braced at the center directly under the center bearing-plate f and 75 has suitable side bearing-blocks f'.

The swinging frame G carries springs g g and is hung from studs d³, secured to the transoms B by links G'. These links are in the present instance within the transoms, so that 80 they are protected. The studs d³ are attached to the outside of each beam D' and pass through openings in the beam, the upper end of each link G' resting between the beams and the flange of the bolster F. The springs 85 I for the boxes are mounted between the plates D D' in the side frames and are also protected.

In some instances I may extend a bottom plate under the swinging plate G from one 90 side frame to the other, so as to inclose the space between the transoms in which the bolster and swinging frame are mounted, as shown by dotted lines in Fig. 1.

It will be seen by the above description that 95 a truck can be made from ordinary metal shapes now on the market in a very cheap and substantial manner and which will be fully capable of withstanding the strains to which an electric-locomotive truck is subjected. At the same time it can be made comparatively light and with very few of the parts exposed, leaving ample room for the motors and their parts.

In some instances I may use the bent channel-beam D' with plain side plates, as shown in Fig. 8, instead of the channel side plates D. The channels D' may be made in two parts secured together; but I prefer to make them from single lengths, which are readily obtainable on the market.

In Fig. 7 I have shown the swinging frame G below the transom and connected to links hung on the outside. This form is preferred when narrow channel-beams are used for the frame of the truck.

I claim as my invention—

1. The combination in a truck structure of channel-beams bent to form the transom and portions of the side frames, with channel-beams forming the side plates of the side frames, the beams being secured together with their flanges abutting and extending over the boxes and forming cavities for the box-springs, substantially as described.

2. The combination in a truck structure, of bent channel-beams and straight beams with plates D² secured to the structure at the junction of the bent channel-beams and straight beams and having openings for the reception

of the dead-levers of the brake mechanism, substantially as described.

3. The combination in a car-truck, of the transoms composed of deep channel-beams, a bolster formed to the shape of a channel-beam, a swinging frame G supporting the bolster, pins on the inner side of the transoms, links hung to the pins and mounted between the transom and bolster and carrying the swinging frame, the said bolster, swinging frame and links being within the space enclosed by the transoms, substantially as described.

4. The combination in a car-truck, of the transom made of two channel-beams, the bolster and swinging frame, its links and springs interposed between the bolster and swinging frame, the several parts being within the transom, substantially as described.

In testimony whereof I have signed my name to this specification in the presence of two subscribing witnesses.

ARTHUR L. CHURCH.
